(57) **CLAIM**

The ornamental design for a coil component, as shown and described.

DESCRIPTION

FIG. 1 is a front view of a coil component according to a first embodiment;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a perspective view thereof;

FIG. 8 is a front view of a coil component according to a second embodiment;

FIG. 9 is a rear view thereof;

FIG. 10 is a left-side view thereof;

FIG. 11 is a right-side view thereof;

FIG. 12 is a top view thereof;

FIG. 13 is a bottom view thereof; and,

FIG. 14 is a perspective view thereof.
